INVENTOR:

F. W. Harris

UNITED STATES PATENT OFFICE

FORD W. HARRIS, OF LOS ANGELES, CALIFORNIA, ASSIGNOR TO BIG ROCK RANCH COMPANY, OF LOS ANGELES, CALIFORNIA, A CORPORATION OF CALIFORNIA

SIDE-LOADING HEARSE WITH FIXED TURNTABLE

Application filed January 26, 1929. Serial No. 335,161.

My invention relates to burial coaches or hearses, that is to say, to vehicles which are adapted to transport caskets, and while particularly applicable to motor vehicles of this 5 type it is not necessarily limited thereto.

It has become the fixed practice throughout the greater portion of the United States to conduct funerals using motor-driven hearses and utilizing automobiles for transporting the mourners. This and the changing traffic conditions in large cities have necessitated certain changes in the method of loading and handling the casket.

The conventional type of hearse which was 15 in use some fifteen or twenty years ago consisted of a horse-drawn vehicle having doors in the rear and through which the casket was inserted and withdrawn.

It is not an unusual thing at the present 20 time for very heavy metal caskets to be used and the difficulties of loading and unloading these caskets from the old style hearse were very great, particularly in cities in which it was necessary to place the hearse parallel 25 with the curb, thus necessitating the pall-bearers carrying the casket down over the curb and into the street before it could be placed in the hearse and necessitating the lifting of the heavy casket through considerable 30 distance to allow it to be placed in the hearse. To obviate these difficulties side-loading hearses have been designed in which a more or less conventional type of automobile body is employed and in which the casket 35 is inserted and withdrawn through the side of the automobile.

Owing to traffic regulations and to the desirability of maintaining more or less conventional lines in the automobile body, the 40 construction of a side-loading hearse presents certain difficulties. Caskets of the larger size tend to fill the greater portion of the body, the casket extending longitudinally of 45 the body, and it is extremely difficult to provide an opening of sufficient size to withdraw the casket without turning.

It is an object of my invention to provide a 50 side-loading hearse in which the insertion and removal of the casket is facilitated and

which will be of relatively simple and sturdy construction.

It is a further object of my invention to provide a side-loading hearse which when closed with the casket inside has the general 55 appearance of a high-class passenger automobile.

It is a further object of the invention to provide means for shielding the casket and the mourners from rain or snow during the 60 loading operation.

Further objects and advantages will be made evident hereinafter.

Referring to the drawings which are for 65 illustrative purposes only:

Fig. 1 is a plan view of a side-loading hearse embodying my invention.

Fig. 2 is a side elevation showing the means for locking the turntable.

Fig. 3 is an elevation partly in section on 70 a plane represented by the line 3—3 of Fig. 1 viewed in the direction of the arrows.

Fig. 4 is a section on a plane represented by the line 4—4 of Fig. 1 viewed in the direction of the arrows.

My invention is applied to a more or less conventional type of automobile body 10 having an engine 11, standard type of chassis, wheels, etc., a driver's seat 12 being provided in the usual position. Access may be 80 had to the driver's seat through conventional doors. Inside the hearse I provide a bearing structure 20 in which an axle 21 is free to rotate, this axle being supported in ball-bearings 22 and 23 and extending up and being secured to a turntable 24. This turntable 24 is of sufficient size to carry a casket 85 which may be locked thereon by suitable means, not shown.

Secured by means of hinges 30 near the top 90 31 of the hearse is a side door 32, this door being adapted to swing up into the position shown in Fig. 4 and extending along the side of the hearse as shown in Fig. 3. Toggle links 33 are provided for supporting this 95 door in the open position. Suitable locking means 34 of conventional design are provided for securing this door in the closed position. A lock 40 is carried on a shaft 41 mounted 100 in suitable bearings 42 on the floor of the

automobile, the lock being operated by a handle 43 and having a dog 44 engaging a slotted opening 45 on the turntable.

5 The method of operation of the invention is as follows:

The door 32 being closed and the turntable 24 being in the position shown in full lines in Figs. 1, 4 and 3, the hearse is driven to the point at which it is desired to load it, 10 no casket of course being carried at this time. The door 32 is then lifted into the position shown in Fig. 4 and forms a canopy or cover extending out over a portion of the sidewalk and under any type of marquee or roof which 15 may be provided. The lock 40 is then released and the turntable is swung out into the dotted position shown at 50 in Fig. 1. In this position it will be noted that the end 51 of the turntable extends out from the side 20 of the hearse into such a position that the pall-bearers holding one end of the casket may walk alongside and deposit their load directly onto the turntable. The casket is then pushed in the direction of the arrow 52 25 into position where it rests wholly upon the turntable and is secured down by any type of catch suited to engage the particular type of casket used, these catches, forming no part of the present invention, not being 30 shown.

The turntable is then swung around in the direction of the arrow 53 so that it assumes the position shown in full lines in Fig. 1 and the lock 40 is operated to lock it in this position. 35 The door 32 is then closed and the hearse is ready to proceed to its destination. When this destination is reached the door 32 is again opened, the turntable is swung out and the casket is removed.

40 I claim as my invention:

1. In a hearse, the combination of: an enclosed body having a length somewhat greater than, and a width somewhat less than, the length of an adult casket to be transported; 45 a door in the side of said body; and a turntable turning about a fixed axis within said body and adapted to support said casket within said body and to turn it about said axis, said axis being adjacent one of the ends 50 of said casket, into a position such that the casket may be removed through the opening normally closed by said door.

2. In a hearse, the combination of: an enclosed body having a length somewhat greater than, and a width somewhat less than, the length of an adult casket to be transported; a door in the side of said body; and a turntable turning about a fixed axis within said body, 55 said axis being located adjacent one of the ends of said casket, said turntable being adapted to support said casket within said body and to swing said casket outwardly through the opening normally closed by said door.

60 3. In a hearse, the combination of: an en-

closed body having a length somewhat greater than, and a width somewhat less than, the length of an adult casket to be transported; a door in the side of said body; and means for supporting said casket within said body, said means swinging about a fixed axis adjacent one of the ends of said casket to turn said casket into a position from which said casket may be readily removed through the opening normally closed by said door. 70

75 4. In a hearse, the combination of: an enclosed body having a length somewhat greater than, and a width somewhat less than, the length of an adult casket to be transported; a door in the side of said body; and means 80 rotatable about a fixed axis within said body adjacent one of the ends of said casket, said means being adapted to support said casket within said body and to swing said casket outwardly through the opening normally 85 closed by said door.

In testimony whereof, I have hereunto set my hand at Los Angeles, California, this 5th day of January, 1929.
